VENTILATOR FOR WINDOWS

Leon Albert Van de Veire, South Bend, Ind.

Application January 10, 1955, Serial No. 480,915

1 Claim. (Cl. 98—99.8)

This invention relates to improvements in ventilators for windows.

The primary object of this invention is to provide a novel, simple device of this character which is adapted to be mounted detachably or removably within the frame of a double-hung window, and which is capable of adjustment between fully opened and fully closed positions.

A further object is to provide a device of this character which is formed of a plurality of sections which are separable and which accommodate collapse of the unit into a small compass, and which are assembled readily and are provided with novel means for locking them in assembled relation within a window frame in such a manner as to prevent separation thereof by unauthorized persons working from the exterior thereof.

A further object is to provide a device of this character with novel means for mounting it and locking it within a window frame.

A further object is to provide a device of this character which may be mounted within a window of any size by simply selecting detachable panels of proper length for the size of the window in question.

A further object is to provide a device of this character which is adapted to close automatically in response to wind velocity or pressure.

A further object is to provide a device of this character which has a novel construction for repelling rain while in selected open position.

A further object is to provide a device of this character having novel means for locking and adjustment thereof.

Other objects will be apparent from the following specification.

In the drawing:

Fig. 1 is an inner face view of the device;

Fig. 2 is an enlarged vertical sectional view taken on the line 2—2 of Fig. 1, illustrating the manner in which the device is mounted within a window;

Fig. 3 is an enlarged fragmentary horizontal sectional view taken on lines 3—3 of Fig. 2;

Fig. 4 is a vertical sectional view taken on line 4—4 of Fig. 3;

Fig. 5 is an inner face view of a retainer employed in the device;

Fig. 6 is an enlarged detail sectional view taken on the line 6—6 of Fig. 2, illustrating the construction of the lock;

Fig. 7 is a detail sectional view of a modified embodiment of the vane;

Fig. 8 is a detail sectional view of another modified embodiment of the vane; and

Fig. 9 is a fragmentary detail sectional view taken on line 4—4 of Fig. 1 and illustrating a modified construction of a louver carrier.

The device is intended primarily for insertion within a window frame 1, as illustrated in the drawing, said window frame being of the conventional double-hung type having an upper sash 2 and a lower sash 3 slidable therein. The frame has a plurality of parallel upright

2

guide strips 4 at each of its opposite sides defining grooves or channels within which the upper sash 2 and lower sash 3 are slidable between open and closed positions. At its bottom the window is provided with a sill 5 inclined downwardly and outwardly, and at its inner surface the window has trim members 6 including a horizontal stool member 7, preferably positioned at a level above the upper surface of the uppermost end of the sill 5, as illustrated in Fig. 2. The window is adapted 10 to receive a frame 8 outwardly of the outer vertical ribs 4 thereof, which frame may either carry glass panes and constitute a storm sash or may carry window screening, as well understood in the art.

My new device comprises a pair of similar ventilator frame members adapted to seat against opposite vertical sides of the window frame, as illustrated in Fig. 3. Each of these frame members preferably constitutes a vertically elongated metal member of substantially uniform cross-section and of substantially channel shape. Thus each member has a base 12 which is substantially flat and whose width will preferably be substantially equal to the spacing between the outermost edges of the guide strips 4 which guide the lower sash 3. From its opposite margins extend substantially parallel portions 13 and 14 which are slightly different in width, the member 13 as here shown being slightly wider than the member 14. Substantially parallel but slightly offset inwardly projecting parts 15 and 16, which are parallel to the base 12, project from the outer ends of the parts 13 and 14, respectively. Substantially parallel flanges 17 project from the inner ends of the members 15 and 16, the same extending substantially perpendicular to the base plate 12 and having their outermost surfaces spaced apart a distance substantially equal to the spacing between the members 4 which guide the lower sash 3. This metal channel member will preferably be of a length slightly less than the height of the lower sash 3, although it may be of any length found suitable and may be substantially shorter than the sash 3. The upper and lower edges of the channel member will preferably be inclined to fit snugly relative to the inclined sill 5 and the inclined bottom surface of the window sash 3.

Each of the channel base members 12 mounts a plurality of brackets or carriers. Thus each of these carriers 45 preferably has a base 21 pivoted intermediate its ends to the channel by means of a rivet or like pivot member 22 extending therethrough and preferably through parts 12 and 15 of the channel as illustrated in Fig. 3. The pivot 22 will preferably be located substantially centrally of the length of the member 21. Side flanges 23 project lengthwise of the plate 21 in parallel relation and are interconnected at one end by an end plate 24. Thus each of the members 21—24 constitutes a socket adapted to receive one end marginal portion of an elongated glass panel or louver 25. It will be understood that cushioning material, such as sheet rubber, felt or the like, may be carried by the channel-forming members 23, 24 to cushion the ends of the glass panels carried thereby, and it will also be understood that flanges or retainers 26 55 may be provided at the upper ends of each of the sockets to retain the glass panels against release, as illustrated in Fig. 9. A sufficient number of sockets and panels will be provided so that the space between the lower sash 3 in its elevated position, as illustrated in Fig. 2, and the sill, which is determined by the length of the channel 12, will be completely spanned by the aggregate of the window panel members 25 when the latter are in the full line closed position illustrated in Fig. 2. At the same time, the glass panels are of such width that they may be swung to substantially horizontal position, as illustrated in dotted lines in Fig. 2, to provide maximum ventilation or air movement through the space between

the bottom of the window sash 3 and the window sill. Note that in the closed position, the panels 25 are located substantially parallel to one another and at substantially a ten degree angle relative to the vertical. The lower portion of each of the glass panels 25 overlaps the upper marginal portion of the glass panel next therbelow so that, when the glass panels are in closed position, a fully waterproof closure is provided. It will also be understood that the channel members and the sockets pivoted thereto constitute preformed units which are handled separately and must be formed in right and left constructions so as to be inserted in place at opposite sides of the window. After insertion of the channels in place, the glass panels 25 of proper length to span the window opening are inserted in the socket members 23, 24 so that the glass panels 25 constitute means for holding the frame parts in proper spaced relation.

Means are provided for simultaneously and equally pivoting the glass panels or louvers. Such means may be located at one only of the channels and is preferably constructed substantially as illustrated in Figs. 3 and 4. An elongated rod or bar 31 of a length less than the overall length of the member 12 is slidably received within the channel chamber defined by the parts 12, 14, 16, and preferably is located in substantially face engagement with the part 16 with its innermost edge adjacent to or bearing against the member 14. Two or more pins 32, anchored at their opposite ends at parts 12 and 16, are located adjacent the outer edge of the member 31 for engagement with said edge to guide the same and, in cooperation with the part 14, hold the same in substantially vertical position, but in a position capable of free sliding motion. A plurality of links 33, equal to the number of socket members 23, 24, are pivoted at 34 at one end to the bar 31 in substantially equally spaced relation juxtaposed to the respective socket members 23, 24. At its opposite end, each of the links 33 is connected by a pivot pin 34' with a lever 35 which is fixedly mounted upon the pivot pin 22, as by means of a cross-pin 36 extending through an aperture therein and in pin 22. It will be understood that the pin 22 is fixedly related to the plate 21 of the glass-receiving socket as by means of splines 37 or lock members, so that movement or swinging of one of the parts 21 or 35 will result in similar and equal rotative movement or swinging of the other of said members 35 and 21. The levers 35 and links 33 may be arranged in any manner found suitable and the relation of the parts will be such that longitudinal movement of the bar 31 will produce similar and equal rocking or swinging movement of each of the pane carriers 23, 24. Thus the members may be arranged substantially as illustrated in Fig. 4, from which it will be seen that any movement of the member 31 will equally swing the respective panes 25 between fully open and fully closed positions.

Any suitable means may be provided for effectively locking the frame members in the window frame so the same cannot be disassembled or dismantled or removed from the window frame. Each of the frames is thus associated with a container member of the construction best illustrated in Fig. 5, and preferably including a flange 41 bent substantially perpendicular from a plate 42 and cooperating therewith to define a member of substantially angleiron shape in cross-section. The member 41 is narrow and is adapted to be interposed between the channel part 16 and the frame part 4. The member 42 is adapted to bear against the inner surface of the channel part 14. The member 42 is located above the stool 7 and is preferably offset at 43 adjacent its lower end to define a step and terminates in a tongue or lip portion 44 which is adapted to bear against the outer edge of the member 7 of the window frame. The member 41 preferably terminates adjacent but above the step 43. The member 42 is bent at its opposite end at 45 and terminates in a lip 46 which is adapted to bear

against the inner surface of the lower portion of the frame of the sash 3. A plate portion 47 projects forwardly and slightly downwardly from the junction of the parts 45 and 46 and is adapted to bear against the inclined bottom face of the lower member of the lower sash 3. An upwardly projecting tongue or lip 48 is formed at the free end of the part 47 and is adapted to bear against the outer face of the lower member of the lower sash 3. Thus the member 41—48 cooperates with the window frame, the lower window sash, and the frame members of my device to hold the latter in proper position when the lower member of the sash 3 bears thereagainst and when the shoulder 43 bears against the part 7 of the window frame. In this connection it will be observed that the plate 42 projects inwardly beyond frame parts 12, 14 and terminates in the paths of pivotal movement of the inner ends of the glass panels 25, as seen in Fig. 3, so as to form a barrier preventing sliding removal of those panels from the receiving sockets 23 and 24 in a selected range of the open positions of said sockets and louvers. Positive means to prevent disassembly of these parts can be provided very simply in the nature of a stick or bar 49 bearing against the top member of the lower sash 3 and against the bottom of the top member of the window frame, so as to prevent raising of the lower sash from the position illustrated in Fig. 2.

Any suitable means may be provided for adjusting the position of the pane-carrying sockets 23, 24. One such means is illustrated in Figs. 2 and 6. In this construction an elongated slot extends vertically in the member 12 at 51 in register with the vertical bar 31. Along the opposite sides of the slot the member 12 is provided with a series of spaced apertures 52. A bracket 53 is carried by the member 31 and extends through the slot 51. In the preferred form the bracket has an upwardly projecting portion 54 and a substantially horizontal terminal portion 55 projecting inwardly from the member 12 and preferably so oriented as to be clear of the members 23, 24 and the glass panels carried thereby in all operative positions thereof. Ears 56 form a part of the bracket 53 and have pivoted thereto at 57 a latch 58 whose shape may be substantially of the character illustrated in Fig. 6 and which terminates in a locking pin 59 adapted to seat in one of the apertures 52. If desired, the member 58 may have two pins 59 spaced apart laterally. The opposite end portion 60 of the member 58 has pivotally connected thereto at 61 a latching lever 62 which preferably is spaced below the member 55 and provided with an upwardly projecting elongated pin 63 around which fits the lower end portion of a coil spring 64 adapted to urge the member 62 away from the member 55. The upper end of the spring 64 will preferably be anchored suitably to the member 55. The arrangement of the parts is such that the spring 64 normally urges the pin 59 into locking position in a socket 52 when registering therewith. However, when the members 62 and 55 are grasped to swing them toward each other against the action of the spring, the locking pins are swung out of the sockets 52, thereby accommodating bodily movement of the bar 31 relative to the frame 12.

In the event it is desired to disengage the latch pins 59, an arrangement as illustrated in Fig. 6 may be employed, which arrangement includes the provision of a hook member 65 which is swiveled at its upper end to the member 55 as at a fixture 66. The lower end portion of the hook 65 is adapted to seat in an aperture 67 in the member 62 when the parts are in the dotted line position shown in Fig. 6, thereby holding the member 59 retracted from the sockets 52 in the members 12. It will be evident, therefore, that the device illustrated in Fig. 6, if associated with a number of spaced sockets 52, may provide for a number of fixed adjusted positions of the glass panels of which one is shown in full lines in Fig. 6. Alternatively, the member may be unlatched completely,

as shown in dotted lines in Fig. 6, so that the panels are free to swing at all times.

One of the glass panel sockets is preferably provided with a vane 70, as illustrated in Fig. 8, extending lengthwise of the glass panel 25 carried thereby along the lower end thereof and upwardly diverging therefrom at an angle of approximately thirty degrees as illustrated. Of course, if desired, more than one of the vanes 70 may be provided. This vane serves as a means to pocket wind gusts acting against the pivoted louvers during such times as the parts are held in released position by the hook 65. It will be understood, of course, that in this connection, the panes 25 and their sockets 23, 24 will preferably be substantially balanced about their pivot axes 22. When this occurs, wind gusts which act upon the panel 25 and the vane 70, as upon the approach of a storm, act to swing the free lower end of the associated vane inwardly, and this movement is translated through the bar 31 and associated links and levers to each of the other vanes 25 so as to automatically close the window upon the approach of storm conditions. Thus with this device a householder need not be concerned about leaving his home with windows open during threatening weather since the device can be adjusted as described above in unlocked position and partially open, thus allowing for ventilation. Such ventilation can continue until such time as an increase in wind velocity or pressure automatically closes the device under storm conditions.

If desired, the device may be provided with a sealing strip upon the inner upper margin of each of the glass panels 25 thereof, as illustrated in Fig. 7. The sealing strip is preferably of channel shape, having web 75 and a pair of flanges or legs 76 and is preferably constructed of rubber or other resilient material adapted to fit the margin of the panel 25. The web 75 is preferably projected at 77 to a slight extent, and this projecting portion will preferably have an inverted groove 78 defined thereby. The strip 75 will preferably extend full length of each glass panel between the sockets which mount it, and will be of such dimensions that the projections 77 bear against the inner face of the next uppermost glass panel 25 when the device is in closed position. The device also functions when the panels are in open position. In this instance the rib defined by the undercut 78 serves as a stop to the flow of liquid which may be blown along the surface of the panel and which normally tends to enter between adjacent panels when the device is either open or closed.

It will be apparent from the foregoing construction that the device is simple in construction and can easily be mounted and dismounted. When dismounted, each of the constituent parts are generally of elongated narrow and substantially flat character so that storage thereof can be effected within a small space. The various operative parts, of course, consist of the two channels 12 and their associated glass sockets and adjusting mechanism, two retainer members 42 and the glass panels 25. Observe that it is not necessary to employ screws, bolts or any other securing means in order to assemble the device, and, further, that it can be locked effectively by the simple expedient of employing a stick or a strut 49 to prevent raising of the lower sash 3 out of engagement with the retainer members 47, 48. Because of the nature of the construction it is apparent that the members 12 and 42 can be made in standard sizes, and as such will fit windows of many different sizes, it being necessary only, to accommodate windows of different sizes, that the glass panels 25 be of a length to span the window. This reduces the number of parts which a dealer must stock

and adapts the device for mass production and distribution, thereby holding costs to the ultimate consumer at the lowest possible level.

It will be observed that the flanges 42 of the retainer members project into the path of pivotal movement of the louvers 25 when the latter are tilted toward horizontal or open position. This relation is best seen in Fig. 3. This serves as a means to retain the louvers within their receiving sockets when the louvers are positioned within a selected range of open position. Furthermore, it will be apparent that the upper part 47 of each retainer in conjunction with the flanges 42 and louvers 25 overlies the ends of and thus serves positively to retain the uppermost louver, in all adjustments thereof. Since the louvers span the ventilator frame between channels 12 at opposite sides of the window frame, the ventilator frame cannot be removed from the window frame until all of the louvers have been removed. Also since the louvers so lock the ventilator frames in the window frame, and since the upper louver cannot be removed until the retainer members 41-48 are removed, it is apparent that the retainer members serve as means to prevent the removal of both the ventilator frame members and the panel members or louvers.

The device has a wide range of adjustment between fully open and fully closed positions and may be locked in any adjustment selected. Alternatively, by maintaining the device in unlocked position, it can be made responsive to wind conditions, so that it will close automatically when storm conditions arise. Still another advantage of the device is its effective sealed condition when closed. Again, as will be apparent from Fig. 2, the device can be installed without interference with the conventional window screens mounted in the frames 8. Retainer part 42 serves to guide window shades and Venetian blinds to prevent interference of the device therewith.

While the preferred embodiment of the invention has been illustrated and described herein, it will be understood that changes in the construction may be made within the scope of the appended claim without departing from the spirit of the invention.

I claim:

A ventilator adapted to be mounted in the frame of a double hung window having a lower sash slideable in vertical guideways, comprising a pair of upright independent frame members each mounted in and projecting from a guideway, a plurality of spaced louver sockets pivoted to each frame member and interconnected for coordinated pivotal movement, a plurality of rigid louvers seating in said sockets at their opposite ends and maintaining said frame members seated in said grooves, each frame member having a longitudinal shoulder, and a retainer member having hooked engagement with said longitudinal shoulder, said retainer interfitting with said sash at one end and hooked to said window frame at its other end, said retainer having a part intersecting the paths of withdrawal of said louvers from said sockets in a selected range of open positions.
